UNITED STATES PATENT OFFICE.

JENS WILLIAM ÆGIDIUS ELLING, OF CHRISTIANIA, NORWAY, ASSIGNOR TO A/S
MYRENS VERKSTED, OF CHRISTIANIA, NORWAY.

REVOLVING SUCTION-STRAINER.

1,377,765.

Specification of Letters Patent. Patented May 10, 1921.

Application filed March 3, 1921. Serial No. 449,497.

To all whom it may concern:

Be it known that I, JENS WILLIAM ÆGIDIUS ELLING, a subject of the King of Norway, residing at Christiania, Norway, have 5 invented certain new and useful Improvements in Revolving Suction-Strainers; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention has for its object a revolving suction strainer suitable for use in mechanical and chemical wood pulp mills, paper factories as well as in other industries.

20 An important feature of the present strainer as compared with known types of revolving suction strainers consists therein that the portion of the strainer which above the level of the liquid in which the strainer 25 revolves is kept covered by an endless belt of a tight material, which prevents air from being sucked into the interior of the strainer at this portion of the strainer surface.

In addition to this feature the strainer is 30 suitably so arranged that the substantial portion of the working surface of the strainer is maintained above the level of the liquid.

An embodiment of this invention is illustrated in the accompanying drawing in 35 which—

Figure 1 is a transverse sectional view of the strainer.

Fig. 2 is a longitudinal sectional view of 40 the strainer.

In this illustrated example the strainer cloth 1 is suspended over ribs on the revolving drum 2 having hollow trunnions 3 rotating in bearings 4. As shown the trunnions of the drum are situated above the edge of the vat 5 so that only a minor part of the strainer surface 1 is immersed in the liquid. An endless belt of oiled canvas (hospital canvas) or other water tight material passes over rollers 6, 7, 8 and rests with its lower run upon the top portion of the strainer. In addition to the endless belt of watertight material an endless belt of felt may be arranged upon which the pulp is 55 taken up from the strainer surface. In this

instance the belt 17 does not rest directly in contact with the layer of pulp upon the strainer surface 1 but on the exterior surface of the said felt. Such felt is not necessary however and may be dispensed with, it having been found that it is possible to take the pulp up directly upon the watertight belt from which it may then be subsequently removed by suitable and well-known means.

In any case the action of the air pressure 60 from outside upon the water-tight belt will result in squeezing water out of the pulp layer between the belt and the strainer surface. The water will flow through openings 65 9 in the wall of the drum and into the suction chamber 11 partitioned in the drum by a transverse wall 10, and from the chamber 11 the water is sucked out through the suction pipe 13 with downwardly directed 70 orifice 12. The pipe 13 extends through the 75 hollow trunnion 3 of the drum, and a stuffing box. This pipe does not rotate with the drum. To prevent air from being sucked in at that portion of the strainer surface, which is situated between the roller 6 and 80 the level of the liquid a slide 14 is arranged, which is pressed against the wall of the suction chamber by means of a spring 15. The slide is hinged to a stationary bar 16 connected to the pipe 13.

The apparatus may be employed in connection with any kind of suspensions from which it is desired to remove the suspended particles.

I claim—

1. A suction strainer comprising a revolving strainer drum with its straining surface arranged to be partially immersed in liquid and non-straining means over a substantial portion of the straining surface not immersed.

2. A suction strainer comprising a revolving drum with its straining surface partially immersed in liquid and an endless belt of a tight material running over a substantial portion of the straining surface which is not immersed in liquid.

3. A suction strainer according to claim 1 in which the substantial portion of the strainer surface is situated above the level of the liquid.

4. A suction strainer according to claim 1, means to prevent air from being sucked into the interior of the strainer drum through such portions at the strainer sur-

face which are not covered by the tight belt nor coated with pulp.

5. A suction strainer according to claim 1 means to prevent air from being sucked into the interior of the strainer drum through such portions at the strainer surface which are not covered by the tight belt nor coated with pulp, said means comprising a slide mounted in the interior of the drum.
- 10 6. A suction strainer comprising a revolving strainer drum with its straining surface arranged to be partially immersed in liquid,

a non-straining means covering a substantial exterior portion of the drum and means within the drum to prevent straining action 15 of said surface between the surface of the liquid and the first mentioned means.

In testimony that I claim the foregoing as my invention, I have signed my name in presence of two subscribing witnesses.

JENS WILLIAM ÆGIDIUS ELLING.
